(57) **CLAIM**

The ornamental design for a motorcycle, toy, and/or replicas thereof, as shown and described.

DESCRIPTION

This application contains subject matter related to the following co-pending U.S. design patent application:

Application Ser. No. 29/668,994, filed Nov. 5, 2018 and entitled "Motorcycle, Toy, and/or Replicas Thereof."

FIG. 1 is a front and left side perspective view of a motorcycle, toy, and/or replicas thereof embodying new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

1 Claim, 7 Drawing Sheets
